CLAIM

The ornamental design for a travel case for an electric dry shaver, substantially as shown and described.

DESCRIPTION

FIG. 1 is a perspective view of a travel case for an electric dry shaver showing my new design;

FIG. 2 is a top plan view thereof;

FIG. 3 is a left side elevational view thereof;

FIG. 4 is a bottom plan view thereof;

FIG. 5 is a rear elevational view thereof;

FIG. 6 is a front elevational view thereof;

FIG. 7 is a perspective view thereof with the top cover in an open position and the interior compartment cover in a closed position; and

FIG. 8 is a perspective view thereof with the interior compartment cover in an open position.
